UNITED STATES PATENT OFFICE.

MARTIN L. KINSEY, OF DOS PALOS, CALIFORNIA.

CORK-EXTRACTOR.

1,225,037.

Specification of Letters Patent.

Patented May 8, 1917.

Application filed May 17, 1916. Serial No. 98,076.

To all whom it may concern:

Be it known that I, MARTIN L. KINSEY, a citizen of the United States, residing at Dos Palos, in the county of Merced, State of California, have invented certain new and useful Improvements in Cork-Extractors; and I do hereby declare the following to be a full, clear, and exact description of the invention, such as will enable others skilled in the art to which it appertains to make and use the same.

This invention relates to cork extractors and has special reference to a cork extractor arranged to impart a rotary motion to the cork during the extracting process.

The principal object of the invention is to provide an improved and simplified cork extractor which will effect the extraction of the cork from a bottle by means of a twisting or spiral movement.

A second important object of the invention is to provide an improved form of cork extractor wherein the elements used to impart a twisting movement to the cork may be held ineffective for such movement until the corkscrew has been properly inserted to carry these elements deep enough into the cork to properly produce the movement without breaking the cork.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a perspective view showing the device about to be applied to a cork;

Fig. 2 is a perspective view showing the device in position ready to extract the cork;

Fig. 3 is a detail view partly in cross section showing a portion of the device including the screw shank and lock bar and showing these parts in binding engagement;

Fig. 4 is a view similar to Fig. 3 but showing the parts in released position.

Fig. 5 is a section on the center line of Fig. 1 and showing the rotatable knife carrying element and its journal.

In the embodiment of the invention herein illustrated there is disclosed a screw 10 of the ordinary type and this screw is provided with a polygonal shank 11 at the upper end

of which is fixed a handle 12. Between the shank and the screw is a cylindrical portion forming a journal and the shank, journal, and screw are formed of one piece of metal. 60 This shank 10 is tapered and has the smaller end of the tapered portion lying adjacent the screw and journal. The taper of the shank is very slight for purposes which will be hereinafter set forth. Rotatably 65 mounted on the journal is a transverse knife bar 14 and carried by this bar and projecting downward therefrom in parallel relation to the screw is a pair of knives 15. These knives 15 are preferably in the form 70 of thin blades pointed at their lower extremities and shaped like a double-edged dagger, the edges lying in a plane radial to the axis of the screw. Fixed above the bar 14 on the shank 11 is a collar 16 which is so 75 arranged as to prevent movement of the bar longitudinally of the shank.

It will be obvious that this collar may be fixed to the cylindrical portion of the shank 80 if desired.

At 17 is disclosed a lock bar and this lock bar is of inverted U-shape and is provided with a central polygonal opening 18 through which passes said shank. The legs of the lock bar are arranged to extend downward 85 over the sides of the knife bar 14 when it is desired to lock the knife bar to move with the shank. The opening 18 is of such size as to be slightly larger than the smaller end 90 of the tapering shank and to fit tightly on the larger end of said shank so that there will be a binding engagement between the lock bar and the shank when the lock bar is raised so that the legs are free from the sides of the knife bar and thus the latter can 95 rotate freely with respect to the screw and shank.

In the operation of the device, when it is desired to pull a cork the lock bar is 100 raised until it binds upon the polygonal shank. The device is then used as if it were an ordinary corkscrew. As the screw enters the cork the blades will be forced downward in straight lines so as to enter the cork to the desired extent. The lock bar is then moved downward to release 105 from the polygonal shank and the legs of the lock bar will engage over the sides of the knife bar so that when further rotation is imparted to the shank the cork will be rotated as the knife bar will be locked to said shank. Thus the cork will be loos- 110

ened in the neck of the bottle and by adding to the rotative movement a very slight pull the cork can be easily extracted without breaking the same and without danger of pulling the screw out of the cork as frequently happens with the ordinary cork-screw.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new is:—

1. A cork extractor including a screw having a polygonal shank and a handle, said shank being tapered with its smaller portion adjacent the screw, a knife carrying element rotatable on the shank adjacent the screw, and a locking device slidably fitted on the shank and engaging said element in one position, the opening in said

device fitting the larger end of the shank in binding relation when out of engagement with the element.

2. A cork extractor including a screw having a polygonal shank and a handle, the upper end of the screw being connected to the shank by a cylindrical portion constituting a journal, the shank being tapered with the smaller end adjacent the screw, a knife bar rotatably mounted on the journal, knives carried by the bar and projecting downward parallel to the screw, a collar fixed above the bar to prevent movement of the bar vertically and a lock bar of inverted U-shape and having a central polygonal opening through which said shank passes, the legs of said lock bar being arranged to embrace the sides of the knife bar when depressed, the opening in the lock bar being of such size as to effect binding engagement of the lock bar on the shank when the lock bar is raised.

In testimony whereof, I affix my signature, in the presence of two witnesses.

MARTIN L. KINSEY.
